UNITED STATES PATENT OFFICE.

OLIVER CROMWELL EDWARDS, JR., OF TROY, NEW YORK.

PNEUMATIC CAISSON.

No. 895,543.

Specification of Letters Patent. Patented Aug. 11, 1908.

Application filed April 30, 1906. Serial No. 314,543.

To all whom it may concern:

Be it known that I, OLIVER C. EDWARDS, Jr., a citizen of the United States, residing at Troy, in the county of Rensselaer and State 5 of New York, have invented certain new and useful Improvements in Pneumatic Caissons; and I do hereby declare the following to be a full, clear, and exact description of the invention, such as will enable others skilled in 10 the art to which it appertains to make and use the same.

This invention relates to improvements in pneumatic caissons, and more particularly to caissons cast of concrete.

15 Among the objects in view is the production of a caisson of minimum expense, and of maximum strength and durability and susceptible of being constructed and transported with facility.

20 With this and further objects in view the invention comprises certain novel constructions, combinations and arrangement of parts, as will be hereinafter fully described and claimed.

25 In the accompanying drawing:—Figure 1 is a top plan view of a caisson incorporating one embodiment of the present invention, a coffer-dam being indicated as superimposed on the caisson proper, and the air and spoil 30 shafts being omitted. Fig. 2 is a longitudinal, vertical, central section, taken on the plane of line 2—2 of Fig. 1. Fig. 3 is a transverse, vertical section, taken on the plane of line 3—3 of Fig. 1, and also of Fig. 2, and 35 looking in the direction indicated by the arrow. Fig. 4 is a similar section taken on the plane of line 4—4 of Fig. 1, and also of Fig. 2. Fig. 5 is a longitudinal, vertical section, taken on the plane of line 5—5 of Fig. 1.

40 Fig. 6 is an enlarged detail transverse, vertical section through the air shaft and surrounding parts. Fig. 7 is a top plan view of a fragment of a modified form of caisson. Fig. 8 is a top plan view of a slightly modified form of caisson in which the vertical studs and diagonal braces of the trusses are 45 incorporated in a continuous wall. Fig. 9 is a longitudinal, vertical, central section through the same. Fig. 10 is a transverse, 50 vertical section taken on the plane of line 10—10 of Fig. 8, and also of Fig. 9, and looking in the direction indicated by the arrow. Fig. 11 is a similar section taken on the plane of line 11—11 of Fig. 8, and also of 55 Fig. 9. Fig. 12 is an outline illustration of a series of caissons disposed for constituting a

bed for a subaqueous tunnel, the coffer-dam wall being indicated in position. Fig. 13 is a transverse section taken on the plane of line 13—13 of Fig. 12. Fig. 14 is a top plan 60 view of a further modification in which the diagonal braces of the trusses are omitted. Fig. 15 is a longitudinal, vertical, central section of the parts seen in Fig. 14. Fig. 16 is a transverse, vertical central section of the 65 parts seen in Fig. 14. Fig. 17 is a longitudinal, vertical section taken on the plane of line 17—17 of Fig. 14, the air and spoil shafts being omitted. Fig. 18 is a top plan view of a further embodiment of the present 70 invention. Fig. 19 is a longitudinal, vertical section, taken on the plane of line 19—19 of Fig. 18. Fig. 20 is a similar section of the same taken on the plane of line 20—20 of Fig. 18, the parts being shown on an enlarged 75 scale. Fig. 21 is a transverse section, taken on the plane of line 21—21 of Fig. 18, and also of Fig. 19. Fig. 22 is a similar section taken on the plane of line 22—22 of Fig. 18, and also of Fig. 19. Figs. 23, 24, 25 and 26 80 are transverse sections through caissons embodying the present invention in slightly modified forms.

As above intimated one of the essential objects of the present invention is the obtaining of a maximum capacity for resisting strains, and largely eliminating the item of expense, and, in carrying out this and other objects, I may incorporate the invention in any one of the several embodiments illustrated in the accompanying drawing, all of which disclose the same general conception incorporating the employment of a truss formation for bracing the walls and roof of the caisson for strengthening the same to resist 95 strains.

In the embodiment illustrated in Figs. 1 to 5 inclusive, I employ a casing consisting of side walls 1—1, and end walls 2—2, preferably cast integral from concrete, suitable steel or iron stiffening bars or rods being embedded in the concrete. It is to be observed that in the construction of the caisson all of the parts are strengthened by embedded steel members. The lower edge of the side and 100 end walls may be beveled, as illustrated, for producing a cutting edge, and the upper edges of said walls are connected by a horizontal, flat roof 5 which is cast integral with the walls. Beneath the roof 5 are arranged 105 transverse braces formed integral with the side walls and connected with the roof 5

by vertical studs 7—7. If desired, longitudinal braces may be provided similar to the transverse braces 6, the transverse braces being sufficient ordinarily, but the longitudinal braces being employed in conjunction with exceptionally large caissons. It is to be noted that each of the braces 6 constitutes a lower chord, while the material of the roof 5 constitutes the upper chord of a truss, the chords being spaced by the studding 7. By preference the lower end of each of the studs 7 is flared at the point of connection with the brace 6. In other words, the vertical studs are preferably provided with incline fillings 8—8 at the point of juncture with the respective brace 6. The working chamber produced by the upright walls 1 and 2 and the roof 5 is further strengthened by suitable knee-braces 8—8 formed integral with and connecting the respective side and end walls with the roof at the point of juncture of the roof with the wall. Each of the knee-braces 8 is provided at each side with a filling 9 for the trihedral angle formed by the intersection of the knee-brace with the vertical wall and roof of the working chamber. Each knee-brace with its filling thus constitute a powerful factor in resisting twisting strains, and also resisting inward crushing strains. At each corner of the working chamber, formed by the juncture of the ends, sides and roof is arranged a filling 10 for the trihedral angle formed by the intersection of the vertical walls and roof of the working chamber.

35 Mounted upon the caisson roof and extending as far above the same as is necessary is the customary cofferdam structure 11, which may be formed of wood, or concrete, or other material as preferred. The cofferdam structure is braced by longitudinal parallel beams 12—12 and transverse parallel beams 12'—12'. In addition to the bracing action of the beams, said beams have the further function of stiffening and strengthening the roof 5 and aiding in sustaining the same, and transmitting strain therefrom to the sides and ends of the caisson. For the purpose of insuring the transmission of strains, each of the beams 12, as clearly seen in Fig. 5, is connected at its ends by vertical posts 13 to the roof and end wall of the caisson. Intermediate the length of each beam 12 are arranged incline braces 14—14 which connect the respective beam to the roof 5, all of said beams and the vertical post 13 being, of course, cast from concrete. By preference, as indicated in Fig. 5, each of the beams 12 is provided with an embedded metallic rod or bar 15, and the roof 5 immediately below the 60 rod 15 is provided with a similar longitudinally arranged rod 16, the two rods being connected at their ends by rods 17—17. This adds tensile strength to the structure and capacity for resisting strain, and, while only 65 one rod has been shown in each member in

the drawing, of course as many rods may be used as are necessary to provide the requisite strength for the member.

In addition to the incline braces 14, at suitable points intermediate the length of each of the beams 12 are preferably arranged vertical studs 18—18, and the rods 15 and 16 are preferably connected by rods 19—19 and 20—20, embedded respectively in the incline braces and in the vertical studs. Each of the transverse beams 12' is constructed as nearly like each of the longitudinal beams 12 as is conveniently possible. Each of the beams 12' is formed integral with each of the beams 12 at the point of intersection, such point of intersection occurring in vertical alinement with one of the vertical studs 7. A tie rod 22 preferably extends longitudinally of the vertical column 23 formed at the juncture of each of the transverse beams 12' with the longitudinal beams 12, said tie rod extending through the roof 5 and longitudinally through the respective vertical stud 7, and through the brace 6. Each transverse beam 12' is provided with incline braces 24—24 intermediate its length and vertical studs 25—25 at its ends connecting the respective beams 12' with roof 5, and preferably cast integral with both said beam and roof. Thus it is to be observed that with a comparatively small quantity of concrete and metal bars or rods, I have been able to produce a structure susceptible of resisting inward crushing strains, and also of resisting twisting strains due to racking of the caisson during operation.

The beams 12 and 12' constitute upper chords of trusses of which the roof 5 constitutes the lower chord, the chords being connected by suitable incline braces and vertical studs. The truss formations make possible the securing of the maximum strength and rigidity with a relatively small quantity of material.

It is to be observed that I have, for the purpose of clearness, omitted from Figs. 1, 2 and 4 the showing of the man and spoil shafts, and have only indicated therein the apertures 26—26 formed in the roof 5 for the reception of such shafts. However, in Fig. 6, I have illustrated in detail a form of connection between each of the shafts and the roof 5. Referring to Fig. 6 it will be seen that the shaft 27 rests upon a plate 28, which is of circular shape and formed angular in transverse section, being preferably a right angle bar. Upon the plate 28, inside the shaft 27, is arranged a ring 29 of angle material which is suitably bolted or otherwise secured to the plate 28, the ring 29 in turn being riveted, or bolted, or otherwise suitably secured to the shaft 27. In order to insure the retention of the parts in their proper position, I preferably provide bolts 30—30 which are headed at their free ends and bent

so as to be embedded well into the material of the roof 5, and beyond their bent portions, said bolts 30, extend upwardly through the plate 28 and ring 29, and are provided with 5 suitable nuts for retaining said plate firmly in position.

In Fig. 6 I have illustrated a broken away portion of concrete filling upon the roof which filling is placed for the purpose of adding weight after operations have begun for insuring the sinking of the caisson.

In Figs. 8 to 11 inclusive I have illustrated a modified embodiment of the invention in which I produce the truss formation by the 15 use of continuous relatively thin walls or webs as substitutes for the vertical and inclined braces. In these figures, I have shown a working chamber made up of side walls 31, end walls 32, and a roof 33. The 20 roof is braced with respect to the side walls by knee-braces 34—34 suitably spaced apart. These knee-braces may, of course, be provided with fillings corresponding to fillings 9, if desired, but such fillings are not illustrated 25 in the drawing. The trihedral angle produced by the union of the side and end walls and roof is provided with a filling 35 preferably made up of knee-braces cast integral with the side and end walls and roof and constructed of polyhedral angle formation. The 30 working chamber is further braced by transverse braces 36—36 cast integral with the side walls and connected with the roof by integral continuous webs 37. Above the roof 35 33 are provided longitudinal parallel beams 38—38 and transverse parallel beams 39—39, each of said beams being formed integral with a continuous web 40—40, which in turn is formed integral with the roof 33. The 40 beams 38 and 39, at their points of intersection are preferably connected with the braces 36 by vertical tie rods 41—41. Thus it is to be observed that the structure seen in Figs. 8 to 11 inclusive corresponds to the 45 structure first described but differs therefrom only in that continuous webs are employed instead of the open work produced by inclined and vertical braces.

A further embodiment of the present 50 invention is illustrated in Figs. 14 to 17 inclusive. The structure seen in these figures involves a working chamber made up of side walls 42 and end walls 43 cast integral, and also formed integral with the horizontal 55 roof 44', the roof being preferably constructed with knee-braces extending continuously of the contacting edges of the roof and the vertical walls. It is to be noted that in the foregoing embodiments the beams or chord 60 members are connected with the roof at their ends by vertical studs, but such structure, while preferred, need not be employed for embodying the essential conception of the present invention as will be seen from Figs. 65 14 to 17 inclusive, in which suitable trans-

verse braces 44—44 are arranged in the working chamber and suitable longitudinal braces 45—45 are also arranged therein, all of said braces extending to and being formed integral with the vertical walls of the working chamber. In the braces 45 will be seen the embodiment of the longitudinal braces above suggested as adapted to be employed in conjunction with the structure seen in Fig. 5, if desired. Of course, the amount of strain to which the caisson is to be subjected and its size will largely govern as to whether or not the longitudinal braces 45 will be employed. At the points of intersection of the braces 44 and 45 are arranged vertical studs 46—46 which are formed integral with the intersecting braces and which are extended to and formed integral with the roof 44. The side and end walls of the caisson extend upwardly above the roof 44' and suitable longitudinal, parallel beams 47—47 connect the end walls, and similar transverse beams 48—48 connect the side walls of the caisson above the roof 44'. The beams 47 and 48 are, of course, preferably cast integral with the side and end walls. At the points of intersection of the beams 47 and 48, which points are in vertical alinement with the points of intersection of the braces 44 and 45, the said beams are connected by vertical studs 48'—48' to the roof 44'. A vertical tie rod 49 extends longitudinally through each of the vertical studs 48' through the roof 44', and through the corresponding stud 46, the tie rod projecting beyond the respective beams 47 and 48 and braces 44 and 45, and being suitably connected therewith. Suitable tie rods longitudinally disposed with respect to the roof and beams or braces may also be employed as indicated in Fig. 17 105 and any other metal bars or rods may be embedded in the concrete as may be found desirable for adding to the strength of the structure. When the span between the studs 48', or between either of the studs 48' and the side or end wall of the casing is of sufficient length to make it desirable to have further bracing, I propose to employ additional studs 48"—48", and when the span between the studs 46, or between either of the said studs and either of the walls of the casing is sufficiently great to make desirable additional bracing, I preferably employ suitable studs 46"—46' within the working chamber corresponding to and in vertical alinement with vertical studs 48" above the roof of the working chamber. A suitable tie rod 49' is preferably provided for each set of studs 48" and 46', and extends longitudinally therethrough and through the roof for 125 connecting the beams 47 and 48 with the corresponding braces 44 or 45.

For the sake of convenience of description, attention is directed to Fig. 7 which discloses a top plan view of a fragment of a structure 130

corresponding to that seen in Figs. 14 to 17 inclusive, with the exception that the walls 43' of the casing are of such area as to produce a square caisson. Therefore, the 5 beams 47^a and cross beams 48^a are of the same length, and the span between one beam and another is the same as between any other two beams. Therefore, when such span is of sufficient size as to require more 10 than ordinary bracing, I provide the studs 48^b, indicated in dotted line in Fig. 7. Of course, the trusses of the working chamber of the structure shown in Fig. 7 may, if desired, be correspondingly braced. The showing 15 in Fig. 7 is incorporated in this application, particularly for bringing out the fact that the present improved caisson may be constructed of any size or shape, and requires only such slight variations in the form 20 of truss employed as are adapted for producing the structure of truss best designed for carrying the strains to which the same may be subjected.

In Figs. 18 to 20 inclusive, I have illustrated 25 an embodiment of caisson which incorporates most of the details embodied in the several different modified forms above set forth, and, therefore, for the purpose of consideration of the specific claims hereinafter 30 presented, the showing in Figs. 18 to 20 inclusive may be accepted as preferred in this application. The structure illustrated in the said Figs. 18 to 20 inclusive, involves a casing consisting of side walls 52—52, and end walls 35 53—53, preferably formed of concrete and cast integral, suitable steel or iron stiffening bars or rods being embedded in the concrete. The upper end of the casing formed of the side and end walls 52 and 53 is closed by a horizontal, integral, concrete cast roof 54. The roof and sides thus constitute a working chamber within which are arranged longitudinal beams 55—55, constituting the lower 40 chords of trusses, the said beams 55 extending throughout the length of the caisson and being cast at their ends integral with the vertical walls. Immediately above the beams 55 are longitudinal beams 56—56, which are formed integral with the roof 54 throughout 45 their length, and at their ends are formed integral with the vertical walls. The beams 55 and 56 are connected at various points intermediate their length by vertical studs 57—57 and 57'—57', and between each two 50 of the vertical studs is disclosed an incline brace 58 which connects the two beams 55 and 56. The open work truss is thus produced, the beam 56 serving as the upper chord and the beam 55 as the lower. Arranged transversely of the working chamber 55 are beams 59—59, which intersect the beams 55 and are formed integral therewith at the 60 points of intersection, the ends of the beams 59 being formed integral with the side walls 65 52. Immediately above each of the beams

59 is a corresponding beam 60, which is formed integral throughout its length with the roof 54, and at the ends is formed integral with the walls 52. As seen clearly in Fig. 22, the beams 59 and 60 are connected by incline braces 61—61, as well as by the vertical studs 57, which occur at the points of intersection of the beams 59 and 60 with the beams 52 and 56. Other bracing members may be employed for connecting the beams 59 and 60 as are found desirable. Thus it is to be seen that I provide trusses extending both longitudinally and transversely within the working chamber, and the said trusses may, of course, as above indicated, be constructed with a greater or less number of connecting members as preferred, or when desirable the connection between the chords of the truss may be made in the form of a continuous web as hereinafter set forth. Above 80 the roof are arranged truss members corresponding to those beneath the same. Longitudinal beams 62—62 are arranged parallel to each other, and spaced above the roof and connected therewith at their ends are vertical studs 63—63. A beam 64 is arranged beneath each of the beams 62, and is formed integral with the roof 54 throughout its length. Suitable vertical studs 65—65 connect the beams 62 with the beams 64, all of 90 said vertical studs being in vertical alignment with corresponding studs 57, and the parts being connected together by vertical tie rods 66—66, as best seen in Fig. 20. Each of the beams 62 is connected with its corresponding 95 beams 64 by means of incline braces 67—67, which are disposed between the vertical studs 65 and connecting the lower end of one of the said studs with the upper end of the next contiguous stud. At the middle of the truss 100 formed by the beams 62 and 64 and the connecting parts, the incline braces 67 are crossed, as indicated, for increasing the strength of the central portion of the truss while the remaining portion of the truss is 105 preferably provided with single incline braces. Transverse beams 68—68 are spaced above the roof 54, and are supported on vertical studs 69—69 at the ends. Arranged beneath each of the beams 68 is a corresponding 110 parallel beam 70 which is formed integral throughout its length with the roof 54. The beams 68 and 70, of course, intersect the beams 62 and 64, and at the points of intersection the studs 65 connect said beams, the 115 beams 68 and 70 being further connected by incline braces 71—71, any further bracing members being employed according to the particular requirements of the given caisson.

As best seen in Fig. 20, each of the incline 120 braces of all of the trusses is provided with a stiffening rod or rods, and each of the vertical studs 57', which is not in alignment with the studs 65, is connected by a suitable tie rod with the roof, the said tie rod extending 130

from below the respective beam 55 to a point above the corresponding beam 64. Each of the beams of each of the trusses is also preferably provided with a longitudinally arranged stiffening rod or bar, and, while one rod is shown as extending beyond the concrete, of course as many rods, bars, or other metallic reinforcements may be used as are necessary, and they may be entirely embedded in the concrete if desired. The roof 54 in addition to being formed integral with the side walls, and also being connected therewith by the trusses within the working chamber, is further braced by knee-braces 72-72 spaced apart along the edges of the roof. The trihedral angle formed at each side of each knee-brace by the juncture of the triangular knee-brace with the vertical wall, and the horizontal roof, is formed with a filling 73 which aids in bracing the structure. The trihedral angle formed at each corner of the working chamber by the juncture of the roof with the sides and ends of the casing is also provided with a filling 74.

As seen in Figs. 23, 24, 25 and 26 the trusses may take various forms best adapted for the particular caisson. In Fig. 23, I have illustrated trusses 75-75, formed with upper and lower chords and suitable incline braces. I have also illustrated a transverse truss 76 in the working chamber consisting simply of upper and lower chords and vertical studs. In Fig. 24, I have shown the trusses 78 and 79 above the working chamber as formed of upper and lower chords connected by a continuous web, and I have also shown the transverse truss 80 in the working chamber as being formed of upper and lower chords connected by a continuous web. In Fig. 25, I have illustrated longitudinal trusses 81, and transverse trusses 82, as composed simply of upper and lower chords connected by vertical studs. I have also illustrated the trusses 83 and 84 in the working chamber as similarly constructed. In Fig. 26, I have shown the longitudinal trusses 85, and the transverse trusses 86, as being formed simply of solid integral webs. The longitudinal trusses 87, and transverse trusses 88, of the working chamber being similarly constructed.

As indicated in Figs. 12 and 13, the present improved caisson is especially well adapted for use in forming the foundation for the sub-aqueous tunnel. A number of the caissons are sunk end to end, and after the same have arrived at the required elevation for forming a good, firm foundation, the working chamber is filled with concrete, as at 50, as indicated in Fig. 13, and then the tunnel walls 51 are cast upon the caisson before the coffer-dam walls are removed.

It is to be noted that some of the trusses employed in some of the structures illustrated, include a portion of the roof for a completion of the truss, and, therefore, for

the purpose of convenience, and for distinguishing the elements referred to throughout the appended claims, I have referred to that portion of each truss which is not a part of the roof as a truss formation, and the term 70 truss formation, I desire construed to cover any portion of any truss illustrated not included in the roof.

As is obvious from Fig. 20, as well as from numerous other figures of the drawing, the 75 cofferdam trusses are superposed relative to the working chamber trusses so that the caisson structure may be properly said to be braced by tiers of superposed trusses, it being obvious that as many tiers of trusses may 80 be employed as are found desirable according to the vertical dimensions of the caisson.

What I claim is:—

1. In a caisson, the combination with vertical inclosing walls, and a roof cast integral therewith for forming a working chamber, of a truss formation connected with the vertical walls and roof for transmitting strains. 85
2. In a caisson, the combination with inclosing walls of a truss extending across the 90 space between the walls, and having its ends cast integral with the walls.
3. In a caisson, the combination with vertical inclosing walls and a roof, of a truss formation arranged within the inclosing walls, 95 and connected to the walls and roof.
4. In a caisson, the combination with vertical inclosing walls, and a roof constituting a working chamber, of a truss chord connecting the vertical walls within the working 100 chamber, and truss braces connecting the chord with the roof.
5. In a caisson, the combination with inclosing vertical walls and a roof cast integral, 105 of a truss chord cast integral with the walls, and a vertical stud cast integral with the chord and with the roof.
6. In a caisson, the combination with vertical inclosing walls, and a roof cast integral, 110 intersecting truss chords connecting said vertical walls, and vertical studs cast integral with the roof and with the chords, for connecting the chords to the roof.
7. In a caisson, the combination with vertical inclosing walls, and a horizontal roof 115 cast integral therewith, of a plurality of knee-brace fillings disposed in the angle produced by the union of the vertical walls and roof, and fillings for the trihedral angles produced by the union of each knee-brace filling with 120 the vertical wall and roof.
8. In a caisson, the combination with vertical inclosing walls and a roof formed integral therewith for producing a working chamber, of bracing beams connecting the walls, and 125 means connecting said beams with the roof, said connecting means being formed integral with the bracing beams and with the roof.
9. In a caisson, the combination with vertical inclosing walls and a roof formed inte- 130

- gral, and integral truss formations arranged above and connecting to the roof, and an integral truss formation arranged beneath and connected to the roof.
5. 10. In a caisson, the combination with vertical inclosing walls and a roof cast of concrete of a concrete truss formation beneath and connected to said roof, a concrete truss formation above and connected to said roof, and means connecting the truss formations.
11. In a caisson, the combination with vertical inclosing walls, and a roof cast of concrete, intersecting brace beams spaced from said roof, and means formed integral with said beams and extending to and formed integral with the roof in connecting the beams to the roof.
12. In a caisson, the combination with inclosing walls, of a brace arranged beneath the said roof and connected to the inclosing walls, a vertical stud connecting the brace with the roof, bracing means arranged above the roof, a vertical stud connecting said last-mentioned bracing means with the roof in vertical alinement with the vertical stud of the first-mentioned brace, and means extending longitudinally through both of said studs and through said brace and bracing means for securing the parts together.
30. 13. In a caisson, the combination with the walls and roof of a working chamber, of intersecting bracing beams spaced from said roof on one side thereof, and bracing beams spaced from the roof on the other side thereof, means connecting all of said bracing beams to the roof, and means for tying all of said bracing beams together.
14. In a caisson, the combination with inclosing walls and a roof producing a working chamber, of a bracing beam spaced on one side of the roof, means connecting said beam with the roof, a bracing beam arranged on the opposite side of the roof, means connecting last-mentioned bracing beam to the roof, and a tie rod connecting said bracing beams together.
15. In a caisson, the combination with inclosing walls and a roof constituting a working chamber of intersecting bracing beams spaced on one side of said roof, vertical studs connecting the bracing beams at the point of intersection to the roof, a bracing beam disposed on the opposite side of said roof, a vertical stud connecting the last-mentioned beam with the roof in vertical alinement with the first-mentioned stud, and a tie rod extending through said studs and securing said beams together.
16. In a caisson, the combination with inclosing walls, and a roof constituting a working chamber, of a plurality of truss formations arranged on one side of the roof and formed integral therewith, and intersecting truss formations also formed integral with the roof.
17. In a caisson, the combination with inclosing vertical walls and a roof cast integral, of a beam spaced from said roof, means cast integral with the beam at its end and connecting the same with the roof, and an intermediate brace cast integral with said beam and also formed integral with the roof.
18. In a caisson, the combination with vertical inclosed walls, and a roof constituting a working chamber, the roof being formed with an aperture, of an annular ring formed of right angle material, one of the angles of the ring being embodied in the material of the roof in position for having the opening of the ring registered with the aperture in the roof, so means for anchoring the plate to the roof, a second plate connected with the first-mentioned plate, and a hollow shaft connected with the second-mentioned plate.
19. In a caisson, the combination with inclosing walls and a roof constituting a working chamber, of intersecting bracing beams spaced from said roof at one side thereof, vertical studs arranged at the points of intersection of the bracing beams for connecting the bracing beams to the roof, a bracing beam spaced from the opposite side of said roof, and a vertical stud connecting the last-mentioned beam with the roof.
20. In a caisson, the combination with a working chamber cast of concrete, of a plurality of trusses arranged within said working chamber and cast integral with the walls thereof.
21. In a caisson, the combination with a working chamber cast of concrete, and intersecting trusses arranged within said working chamber and cast integral with the walls thereof.
22. In a caisson, the combination with a working chamber, of trusses arranged therein and cast integral with the side walls and roof thereof.
23. In a caisson, the combination with a working chamber cast of concrete, and a truss cast within said working chamber integral with the roof and side walls thereof, and tie rods extending through the roof and engaging the truss transmitting strains.
24. In a caisson the combination with a rectangular casing and a roof therefor, of a filling of trihedral form for each of the corners produced by the union of the walls of the casing with the roof.
25. In a caisson, the combination with an inclosed concrete casing, of tiers of superposed trusses formed integral with said casing.
26. In a caisson the combination with a casing formed of walls bearing angular relation to each other and a roof therefor, of a filling for each corner produced by the junction of two of the walls of the caisson with the roof.
27. In a caisson, the combination with an

inclosing casing, a brace extending across the inclosure and formed integral with the walls of the casing, and knee braces at the ends of said braces and formed integral therewith 5 and with said walls.

28. In a caisson, the combination with an inclosing casing, and a roof connecting the walls thereof and spaced above the lower end of said walls for forming a working chamber, 10 of a brace extending across said working chamber and formed integral at its ends with the walls of said casing, and a knee brace at each end of said brace formed integral therewith and with the respective walls 15 of the casing.

29. In a caisson, the combination with an inclosing casing, a roof therefor, a brace connecting the walls of said casing above said roof and formed integral with said walls, and 20 a knee brace at each end of said brace and formed integral therewith and with the respective walls of the casing.

30. In a caisson, the combination with an inclosing casing and a roof therefor, of a 25 brace extending across the inclosure of said

casing and connected at its ends to the walls of the casing, and an upright brace formed integral with the first mentioned brace and connected with said roof.

31. In a caisson, the combination with inclosing walls and a roof therefor, of a truss extending across the inclosure formed by said walls and connected at its ends to the walls and connected at its edge to the roof, and a truss arranged at right angles to the 35 first mentioned truss and connected to the roof.

32. In a caisson, the combination with inclosing walls and a roof therefor, of a truss arranged within the inclosure produced by 40 said inclosing walls and disposed for strengthening the roof, and a truss arranged at right angles to the first mentioned truss and also disposed for strengthening the roof.

In testimony whereof I affix my signature 45 in presence of two witnesses.

OLIVER CROMWELL EDWARDS, JR.

Witnesses:

HENRY COLVIN,
D. W. CHAMBERLIN.
